DOOR HANDLE

Lewis A. Jarvis, Grand Rapids, Mich., assignor to
W. B. Jarvis Company, a corporation of Michigan

Application April 1, 1933, Serial No. 663,899

2 Claims. (Cl. 292—348)

My invention relates to improvements in rotatable door handles and latch operating mechanism, and to an improved method of assembly of the parts.

5 My invention is particularly adapted for use for automotive vehicle doors, although it may be employed in manufacturing any type of door operating mechanism. Heretofore in the art, the door operating handle and the rotatable latch operating shaft have been united during the casting operation by inserting the steel operating shaft in the handle die and then die casting the handle around one end of the steel shaft or latch operating element to join the parts together.

10 15 This method of uniting the handle and latch operating element requires the complete forming of a handle for each different size of shaft element, and in re-plating worn die cast handles the plating process often undesirably affects the steel shaft elements causing them to be under-sized in their squared dimension.

20 25 The improved door handle and latch operating shaft of my invention overcomes these difficulties. It is economical to manufacture and simple and efficient in design.

It is an object of my invention to provide an improved door handle and latch operating shaft which is of two part construction and assembled together after the casting and plating operations 30 of each of the parts has been completed, which is easy to assemble and economical to manufacture and wherein the same size and design of handle may be used interchangeably with different sizes and types of handle shaft elements, and 35 all of the parts may be completely formed and subsequently assembled together after forming by a single joining operation.

Many other objects and advantages will readily become apparent throughout a reading of the 40 following detailed description and accompanying drawing, in which:

Figure 1 is a side elevation of a portion of an automotive vehicle door illustrating the latch bolt operating handle of my invention mounted thereon, parts being broken away to illustrate the door latch.

Figure 2 is an enlarged plan view of the door handle and latch bolt operating shaft of my invention shown in assembled relation, with part 45 of the escutcheon plate broken away to illustrate certain details more clearly.

Figure 3 is a cross-sectional view taken on the line 3—3 of Figure 1.

Figure 4 is an enlarged cross-sectional view 50 taken on the line 4—4 of Figure 3, and

Figure 5 is an exploded view of the latch bolt operating door handle and shaft of my invention illustrating the parts in separated position and illustrating a modified type and size of latch operating element.

5 Referring now to the drawing in detail, in which like reference characters designate like parts throughout the several views, I have illustrated in Figure 1 an automotive vehicle door 7, latch mechanism 8 and latch bolt 9 together with the 10 improved rotatable door handle 10 of my invention operatively associated therewith.

The door handle and latch bolt operating shaft of my invention is of two piece construction. The handle 10 may be formed by zinc die casting, 15 stamping steel or brass parts, solid brass casting, or may be formed of plastic material such as cellulose or phenolic condensation products, for example, or of any other desirable material. However, I prefer to make the handle by zinc die casting, and have illustrated that specific embodiment of the invention in the drawing and in the following description. The zinc die casting is completely formed and chromium plated, if desired, and the rotatable handle shaft 11 is completely formed independently of the die cast handle 10 and it is preferably of steel or any other desirable relatively hard substance, and generally is cadmium plated. The parts are assembled together after they have been completely formed in 30 the novel manner hereinafter to be described.

The die cast door handle 10 has a cylindrical sleeve or shank 12 cast integral therewith having a central squared opening 13 formed axially therein, as illustrated in Figures 3, 4 and 5. An 35 annular shoulder 14 is formed around the outer periphery of the cylindrical shank 12 to provide a seat for the escutcheon plate 15 which has a central annular opening 16 formed therein adapted to surround the shank 12.

40 The latch bolt rotating element or handle shaft 11 is of squared design and is known in the trade as a "chill", and is adapted to engage the roll-back of the door latch to cause it to be withdrawn when the door handle is rotated in a manner well known in the art but not shown in the drawing. The inner squared end of the shaft 11 is adapted to fit snugly within the squared opening 13 of the shank 12 of the handle in a manner to effect a drive fit connection. When this shaft is cadmium plated, it will form a surface which more snugly adheres to the inner surfaces of the squared opening 13 of the shank 12. The squared shaft 11 is provided with an annular peripheral groove 17 near its inner end as illustrated in Figures 3 and 50 55

4. As illustrated in Figs. 2, 3 and 5, the outer peripheral surface at a point spaced from the inner end of the shank 12 has a pair of diametrically opposed notches 18 formed therein either during 5 the die casting operation or afterwards, for the purpose of aiding in locking a part thereto as will be hereinafter described.

The die cast handle 10 and shaft 11 are then joined together in the following manner. The 10 escutcheon plate 15 is placed upon the shank 12 in abutment with the shoulder 14 thereof, and a thrust washer 19 (Fig. 5) is slipped over the reduced inner end of the shank 12, as shown in Figure 3. A compression spring 20 is next slipped 15 over the reduced inner end of the shank 12 and a cup washer 21 having a small tubular end relatively closely receiving the small end portion of the shank 12 and an enlarged tubular end 22 is placed over the inner tubular end of the shank 20 12 enclosing the compression spring 20 in its enlarged portion 22. The squared steel shaft 11 is then inserted within the squared opening 13 of the shank 12 to a depth to align the annular groove 17 of the shaft 11 with the aligned diametrically opposed notches 18 formed in the outer periphery of the die cast handle 10. With the 25 spring 20 compressed, as illustrated in Figure 3, and the parts thus assembled in position, the complete unit is placed together and held in this position 30 by any suitable fixture desired and placed in a punch press well known in the art but not shown in the drawing, so that the jaws of the press will close on the small end of the cup washer 21 above and below the diametrically opposed notches 18 of the inner end of the sleeve 35 of the die cast handle. The jaws of the press are then caused to approach each other to displace some of the die cast metal of the shank 12 into the annular groove 17 of the shaft 11, thus 40 joining these two parts together against axial displacement and simultaneously forcing some of the metal of the cup washer 21 into locking relation with the notches 18 of the shank 12, to hold all of the component parts together in the desired 45 relationship. The compression spring 20 will permit the desired movement between the escutcheon plate and the operating parts of the door handle and prevent rattling of the various parts.

The die cast handle 10 and the steel latch operating shaft 11 are thus operatively joined together and the spring pressed escutcheon plate is thus mounted in place by a single press operation. Figures 3 and 4 illustrate the manner in which part of the die cast metal will flow in the 55 annular groove 17 of the steel shaft 11. The escutcheon plate may be joined to the door 7 by screws 23, or in any other well known manner.

It will be noted in Figure 5 that I have illustrated a modified design and size of latch operating shaft 25. This shaft may be of steel and cadmium plated in the same manner as the shaft 11, heretofore described, and is provided with an inner end of the same size as the inner end of the previously described shaft 11 having an annular groove 17 thereon by which the shaft 25 may be secured to the die cast handle 10 exactly as has been described. Any size, length, or design of shaft 11 may thus be provided to fit the same die cast door handle 10, and different sizes and types of latch operating shafts may be interchangeably joined to a single type of die cast handle.

This feature is very important, for example, in the manufacture of this type of door handle for use in automotive vehicles in which different

lengths of operating shafts may be required for different types of bodies, such as sedans, coupes, roadsters and convertible body types by a single car manufacturer, although the same size and design of handle is used throughout the entire line of that particular manufacturer. In the manufacture of the door handles of my invention, a large number of die cast handles 10 of the proper design may be formed and plated, and subsequently orders may be filled for the use 10 of these handles with various quantities and types of latch operating shafts, thus it is not necessary for the door handle manufacturer to stock up large numbers of all different types which might become obsolete due to a change 15 of dimension of the operating shaft.

The device of my invention also has great utility in the event that it becomes necessary to re-finish the die casting handle or replate it, since in replateing a single piece handle and steel operating shaft which have been cast together, the stripping operation used to remove the plating prior to replateing affects the steel members and causes them to become undersize in their squared dimensions. In the replateing operation, the operating shaft is also affected and may become oversize in its squared dimension. In view of the fact that the necessity of replateing a handle in production is generally determinable immediately after the plating operation is completed, there is no necessity in the use of the present invention of subjecting the cooperating "chill" or shaft to the action of either the plate stripping operation or the replateing operation, and the disadvantages formerly arising in this connection are 30 35 thus eliminated.

The method of joining the two part handle and shaft of my invention together is more economical, simple and efficient than any heretofore known in the art, and the complete joining of all 40 the component parts together in one operation greatly reduces the manufacturing cost.

Formal changes may be made in the specific embodiment of the invention described without departing from the spirit and substance of the 45 broad invention, the scope of which is commensurate with the appended claims.

I claim:

1. The combination of a door handle having an integral cylindrical shank, said shank having a 50 square sectioned opening therein, a square sectioned shaft grooved near one end and disposed within the opening in the shank, an outer peripheral shoulder on said shank, an escutcheon plate adapted to surround the shank and abut said shoulder, a compression spring surrounding the inner end portion of said shank and abutting at one end against said escutcheon plate, a cup washer surrounding the inner end of said shank and having an enlargement partially enclosing 55 said spring, said washer being provided with a shoulder abutting the other end of said spring to compress the latter and urge the escutcheon plate against the shoulder on said shank, said cup washer and shank being deformed radially inwardly toward the groove in the shaft to maintain the parts in assembled relation.

2. The combination of a door handle having an integral cylindrical shank, said shank having a square sectioned opening therein and being provided with an outer peripheral shoulder thereon, a square sectioned shaft grooved near one end and disclosed within the opening in the shank, an escutcheon plate adapted to surround the shank and abut said shoulder, a compression spring sur- 70 75 80 85 90 95

rounding the inner end portion of said shank and abutting at one end against said escutcheon plate, a cup washer surrounding the inner end of said shank and having an enlargement partially enclosing said spring, said washer being provided with a shoulder abutting the other end of said spring to compress the latter and urge the es-

cutcheon plate against the shoulder on said shank, intermediate portions of both said washer and said shank being deformed radially inwardly toward the groove in the shaft to maintain the parts in assembled relation.

5

LEWIS A. JARVIS.
